US00D481995S

(12) United States Design Patent **(10) Patent No.:** **US D481,995 S**
Yokota **(45) Date of Patent:** **** Nov. 11, 2003**

(54) RECHARGEABLE BATTERY

(75) Inventor: **Hiroaki Yokota, Tokyo (JP)**

(73) Assignee: **Sony Corporation, Tokyo (JP)**

(**) Term: **14 Years**

(21) Appl. No.: **29/174,630**

(22) Filed: **Jan. 23, 2003**

(51) LOC (7) Cl. **13-02**

(52) U.S. Cl. **D13/103**

(58) Field of Search D13/103; 429/96-100,
429/159, 162, 163, 176

(57) CLAIM

The ornamental design for a rechargeable battery, as shown
and described.

DESCRIPTION

FIG. 1 is an enlarged perspective view of a rechargeable
battery showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
